*I Eastman,
Water Wheel
Patented Sep. 28, 1831.*

Joel Eastman, Bath, New Hampshire
Letters Patent

The Schedule referred to in these Letters Patent and making
part of the same containing a description in the words of the said
Joel Eastman himself of his improvement in the Water
Wheel and application of Water thereunto.

To all whom it may concern.

Be it known that of Joel Eastman of Bath in the County
of Grafton and State of New Hampshire, have invented a
new and useful improvement in the construction of the Water
Wheel and the application of Water thereto and that the
following is a correct description thereof.

To a vertical or horizontal shaft attach two or more flouts
made of wood or iron their proper proportion being about two
feet long and one foot wide making a wheel four feet in diameter
etc and one foot long. This wheel is enclosed in a light case
or case fitting the wheel closely and making part of the close
trunk or penstock extending from the flume into the dead
water at the bottom of the fall. Should the necessary power
and motion require it two or more wheels may be attached
to the same shaft each wheel having its own water con-
veyed to and from it separate from the others. For a
vertical shaft there should be a penstock or close trunk ex-
tending as high as the opening for the escape of water from
the upper wheel and into the water at the bottom of the fall
into which penstock the water passes through an opening from
each wheel, each opening being not less than five times as
large as that by which the water is admitted to the wheel
On a horizontal shaft there should be an opening at each
end of each wheel for the escape of water. A in the accom-

4/28/62

Drawing represents a shaft b.b.b. the float. C the cover or case one side of which is omitted for the purpose of more clearly depicting the structure. D the aperture through which the water is admitted to the wheel. E a circular opening round the shaft through the side of the case for the escape of the water from the wheel.

D a gate or valve. What I claim as my invention is a water wheel constructed in the manner above described being enclosed in a case. The case being connected with and forming part of a light framework or frame extending the whole height of the jail. And the application of water to the wheel in the manner above explained. However the same may be varies in proportion.
